UNITED STATES PATENT OFFICE.

SAMUEL B. WAXMAN, OF BALTIMORE, MARYLAND, ASSIGNOR TO L. GREIF & BRO. INCORPORATED, OF BALTIMORE, MARYLAND, A CORPORATION OF MARYLAND.

TROUSERS.

Application filed June 6, 1922. Serial No. 566,316.

To all whom it may concern:

Be it known that SAMUEL B. WAXMAN, a citizen of the United States, residing at Baltimore, in the State of Maryland, has invented certain new and useful Improvements in Trousers, of which the following is a specification.

This invention relates to improvements in trousers and is particularly directed to trousers that are made from thin fabrics for summer wear, such as mohair cloth, although the improvement is as readily applicable to trousers made of other and heavier fabrics.

15 Trouzers of the kind referred to, especially in the case of mohair fabrics, are subjected to strains across the seat when the wearer sits or stoops, which frequently causes the fabric to split because of its brittle character.

The object therefore of my invention is to provide an improved construction and arrangement of stay by which the garment may be reinforced across the seat to the inner seam in the legs and to secure these stays to the fabric by stitching in such a way that the stitches will not be visible on the outer side of the fabric.

25 The invention is illustrated in the accompanying drawing, wherein,—

Fig. 1. shows the upper portion of a pair of trousers wherein the invention is embodied,—the view being a perspective one with a portion of the front of the trousers broken away to better disclose the interior structure.

Fig. 2. illustrates the two separated rear parts of the garment as viewed from the inner side with the stay strips and lining parts laid thereon and ready for attachment thereto, and

40 Fig. 3. shows on a much enlarged scale a cross-sectional detail through one of the stay-strips and a portion of the trouser fabric to show that the attaching threads of the stitching do not extend all the way through to the outer side of the trouser fabric,—the section being taken for example on the line 3—3 of Fig. 1.

50 Referring to the drawing the numeral 5 designates the body-part of the trousers and 6 the leg-parts thereof. The garment also has a front fly 7, a rear seam 8 and inseams 9 in the legs, all of which are of the usual construction.

At the rear the body-part 5 is provided on each side of the seam 8 with two narrow fabric stay-strips 10. These stay-strips have their upper ends 11 stitched at or adjacent to the waistband, from which point they extend downwardly along the inner side of the seat-part 12, while their lower ends 13, project forwardly and downwardly some distance below the crotch 14 and terminate at and are stitched in the inseams 9, as shown in broken lines in Fig. 1. of the drawing.

These narrow stay-strips 10 lie in close contact with the inner surface 15 of the trouser-fabric 16, and are secured thereto by rows of stitches 17. These stitches 17 are so engaged with the trouser-fabric 16 that they do not pass all the way through the latter and therefore are not visible on the outer surface of such fabric, but they do extend all the way through the stay-strips 10.

It is therefore to be understood that the stay-strips are in close contact with and are stitched to the inner side of the seat and upper leg-portions of the trousers so as to prevent undue strain on the thin mohair fabric, but the stitches which secure those strips do not pass all the way through the mohair and are not visible on the outer side thereof.

55 To provide additional protection and reinforcement in the seat of the trousers I also make use of linings 18, which latter cover the stay strips at the seat and are also secured by stitches 19 to the inner side 15 of the trouser fabric. These stitches 19 are also taken in the trouser fabric so as not to extend all the way through the latter.

From the foregoing explanation it is to be understood that I have devised a novel construction and arrangement of reinforcing stays for trousers, particularly of thin light-weight material, which stays extend through the seat-part of the garment and down into the legs and are stitched to the inner surface of the fabric by stitches which latter are invisible on the exterior of the fabric.

Having described my invention, I claim,—

1. A trouser garment having a body and leg-parts and provided with the usual inseams in the legs, said trouser having narrow fabric stay strips whose upper ends are stitched to the inner side of the trousers about the waistline and which extend down

along the inner side of the seat and project forwardly into the legs below the crotch the lower forward ends of said narrow fabric stay-strips being stitched in the inseams of 5 the legs below the crotch of the garment.

2. A trouser garment having a body and leg-parts and provided with a rear center seat seam and with inseams in the legs said trouser having at each side of the rear seat 10 seam a narrow stay-strip of fabric which strips extend from the waistline down along the inner side of the seat and project for-

wardly and terminate in the legs below the crotch said forwardly-projecting ends of 15 said stay-strips being stitched in the inseams and the side edges of the strips being secured to the fabric seat of the trousers by stitches which stitches extend only part of the way through the trouser-fabric from the inner toward the outer side of the said fabric whereby the stitches will be concealed from view on the outer side of the fabric.

In testimony whereof, I affix my signature.

SAMUEL B. WAXMAN.
